ATTORNEY —

UNITED STATES PATENT OFFICE.

DAVID E. FOSTER AND ROBERT J. COLEMAN, OF BALTIMORE, MARYLAND.

DESIGN FOR AN ICE-SHAVE.

SPECIFICATION forming part of Design No. 27,573, dated August 24, 1897.

Application filed June 21, 1897. Serial No. 641,713. Term of patent 7 years.

To all whom it may concern:

Be it known that we, DAVID E. FOSTER and ROBERT J. COLEMAN, citizens of the United States, residing at Baltimore, in the State of Maryland, have invented and produced a new and original Design for Ice-Shaves, of which the following is a specification.

Figure 1 is a side view of our ice-shave. Fig. 2 is a top view of the same.
10 As shown in the drawings, the design consists of a cup-shaped body A with a circular top b and having a flat bottom c and a flange d flush with the bottom and which projects horizontally forward beyond the line of the 15 circular top. An inclined web e is central on top of said flange and adjoins the body. At the rear of the body and adjoining its base is

an inclined face f, the upper part of which projects off from the body, and a handle g has a curved portion g' attached to the said off-projecting part of the inclined face. 20

The ice cutter or blade projects from the flat bottom.

Having thus described our invention, we claim—

25 The design for ice-shaves herein shown and described.

In testimony whereof we affix our signatures in the presence of two witnesses.

DAVID E. FOSTER.
ROBERT J. COLEMAN.
